UNITED STATES PATENT OFFICE.

CHARLES J. DONNELLY, OF PHILADELPHIA, PENNSYLVANIA.

MATCH-MAKING MACHINE.

SPECIFICATION forming part of Letters Patent No. 450,405, dated April 14, 1891.

Application filed February 15, 1890. Serial No. 340,653. (No model.)

To all whom it may concern.

Be it known that I, CHARLES J. DONNELLY, a citizen of the United States, residing in the city and county of Philadelphia, State of Pennsylvania, have invented a new and useful Improvement in Match-Making Machines, which improvement is fully set forth in the following specification and accompanying drawings.

10 The invention relates to certain improvements in machines for coiling match-splints between tapes or webbing and cutting the same preparatory to dipping or heading them; and it consists, first, of a cutting and separating 15 device, as hereinafter described; second, of an automatic stop for stopping the bundling of the splints when the proper-sized bunch has been made by removing the splints in the hopper from the drum; third, of a device for 20 agitating and separating the splints in the hopper, and, finally, of the combination and arrangement of parts, as herein described.

Figure 1 represents a side view of a machine embracing my invention. Fig. 2 represents a top plan view. Fig. 3 represents a 25 sectional view on line $x-x$, Fig. 2. Fig. 4 represents a detail view showing the ball-bearing tension device at end of the weighted lever-arm. Fig. 5 represents a view of the 30 splint-separating device.

Similar letters of reference indicate corresponding parts in the several figures.

Referring to the drawings, A designates the standard or frame of a match-machine having 35 the hopper B secured thereto. C designates the driving-shaft journaled in the frame A and having the driving-pulley or wheel D thereon. A pinion E on the shaft C meshes with a gear-wheel F on the drum-shaft G, 40 which latter has bearings in the frame A. The drum H, which is mounted on said shaft G, has the side and central portions $a-a$ of its periphery, which fit into an opening in the hopper, fluted, so as to readily receive the 45 splints, while the intermediate portions a' of the periphery are grooved or depressed below the fluted portions for the admission of the binding tapes or webbing.

Mounted on a shaft J, having bearings in 50 an arm or extension K at one end of the

frame, are spools or drums L, carrying the tapes or webbing M, which latter are passed around the rollers $b-b'-b''$ and around the drum in the grooved portions a' thereof. The inner ends of the tapes are wound around 55 spools or drums mounted on a shaft or spindle N', having bearings in a swinging arm N, the lower end of which is secured to a sleeve loosely mounted on the shaft P. A sprocket-wheel Q on the shaft P is connected by the 60 sprocket-chain R with a sprocket-wheel Q' on the shaft or spindle N', so as to communicate motion thereto. A train of gearing S T U conveys motion from the gear-wheel F of the drum-shaft G to the shaft P, on which the 65 gear-wheel U is mounted.

Pivotedly connected to the frame A is a weighted lever V, having its unweighted end passing through a vertical elongated opening or slot c in the arm N and provided with a 70 notch or recessed portion d, the object of which will be hereinafter explained. Bearing against the lever V is a spring V', secured to the arm N. Rigidly connected with the shaft of the lever V are arms W, the curved 75 ends of which are normally below the periphery of the drum H. A weighted elbow-lever X, pivoted to the frame A, has at its upper end a ball-and-socket connection Y, provided with the short arms e, having the rollers f 80 thereon. The rollers f bear against the tapes or webbing M, thus controlling the tension of the same.

Journalized in the upper part of the frame A above the drum H is the shaft Z, on which 85 is mounted a pinion Z', which meshes with a gear-wheel B' on the shaft C'. The latter shaft carries a knife or cutter D', adapted to cut the splints in two parts or in regular match-lengths before they are bundled. In 90 the central portion of the periphery of the drum is a groove adapted to receive the cutting-edge of the knife, so that the same may rotate below the level of the splints. A separator E' is secured to the frame between the 95 cutter and the spindle N' and consists of a wedge-shaped piece of material adapted to separate the ends of the severed parts of the splints, so that they can be wound upon their respective tapes or webbing without contact 100.

with each other. The end F' of the hopper is pivoted at its upper end, so as to be adapted to swing freely, and has secured to it a rod G', eccentrically connected with a pinion H', 5 meshing with a gear-wheel J', mounted on the shaft J^x, suitably journaled in the frame A and gearing with a pinion Z² on the shaft Z. A pinion E² on a shaft J^x engages with the gear-wheel F, so as to rotate the said shaft Z. 10 The bottom of the hopper is preferably inclined or sloping in a direction leading from the drum, and the end F' is also inclined, as shown, for the purpose of better agitating the splints and feeding them to the drum. 15 Mounted on the shaft Z, and partly projecting into an opening H² in the hopper between the wall thereof and the drum H, are rotary brush wheels or rollers J², which come in contact with the splints and prevent their 20 crowding between the walls of the hopper and the drum.

The operation is as follows: The match-splints are placed in the hopper B, and motion being communicated to the driving-shaft 25 C by means of the driving-pulley D the drum H is rotated by its connecting-gears E and F. The train of gearing E², J', and H' imparts an oscillating motion to the end F' of the hopper, so that the splints are agitated or shaken 30 so as to be separated, and are also pushed forward to the drum H, so as to be reliably fed to the same. The fluted portions a a a receive the splints above the tapes or webbing M, and as the drum rotates carries them to 35 the cutter D', rotated by means of connecting-gearing Z' B', where they are cut in two. As the drum still further rotates and the severed ends of the splints come in contact with the sides of separator E', the ends of the splints 40 are forced apart, as shown in Fig. 5. At the same time motion is communicated to the spools on shaft N' by means of sprocket-wheels Q Q' and gearing S, T, and U, so that the tapes or webbing M are wound thereon, the 45 splints being inclosed therein, as shown in Fig. 1. Owing to the arm N being loosely mounted on the shaft P, as the coil of wound splints increases in size the said arm rides on the lever V until the notch d is reached, 50 when the weighted end of the lever falls and, the unweighted end rising, the arms W are thrown upward, removing the splints from the drum, so that they are no longer fed thereto. When it is necessary to remove the 55 roll of splints after a sufficient quantity have been wound or otherwise treat the same, the arm V operates, as above set forth, to stop the feed of the said splints to the drum and disengage the splints. In case of any possible 60 inequality or difference of speed in the two tapes, the ball-and-socket connection Y, permitting a slight turning of the same on its bearing, assists in lessening the friction, while at the same time aiding in maintaining a uniform tension. As the coil of wound 65 splints on the spool on the spindle N' becomes larger, a difference of speed is necessary be-

tween the sprocket-wheels Q Q' and the gear-wheels U on the shaft P. To effect this, the sprocket-wheel Q, which is mounted on the said shaft, has between it and the gear-wheel U, which is splined on the said shaft and a clamping-plate U', the leather washers U², the nut U³ on the threaded end of the shaft P binding the said sprocket-wheel Q and the gear-wheel U close enough together that the wheel Q is rotated by the movement of the wheel U, but at the same time is permitted to slip on its shaft as the coil of wound splints becomes larger, and the time of a rotation of the sprocket-wheel Q on the spindle-shaft is thereby lessened, so that the said wheel Q' may move in unison with the wheel Q. After the splints in the hopper have been removed by the arms W from contact with the drum, the spindle N' still rotating, several folds of the tapes or webbing are wound around the coil, so as to firmly secure the splints in place.

The gear-wheel U and the sprocket-wheels Q Q' may be preferably mounted on a stud 90 adjustably secured in a vertically-slotted bearing R', secured to the frame A, instead of on the shaft P, so that the sprocket-chain R may be kept in proper condition on the sprocket-wheels Q and Q'.

The knife may be removed and a single web-wheel inserted, after which full-length sticks may be rolled in a coil in the webbing. In this case the sticks are dipped at either 100 or both ends and cut in two as they are removed from the said coil. For rolling or coiling full-length sticks both tapes or webbing are employed.

Having thus described my invention, what I claim as new, and desire to secure by Letters 105 Patent, is—

1. A match-making machine having a hopper, a drum, a winding device, a cutter, a separator between said cutter and winding device, parallel continuous tapes passing 110 around said drum and receiving thereon the splints from the hopper and binding them around said winding device, and a device for throwing the splints out of engagement with the drum, substantially as described.

2. In a match-machine, a frame with a hopper, a rotary drum, a rotary cutter, a swinging arm with rotary spool thereon, parallel continuous binding-tapes passing around said drum, receiving splints thereon and binding them on the said rotary spool, a separator between said cutter and spool, a device for throwing the splints out of engagement with the drum, and a tension device, substantially as described.

3. In a match-machine, a frame with hopper, a rotary drum feeding from said hopper, a swinging arm with rotary spools thereon, a cutter between said hopper and rotary spool, and a separator between said cutter and spool, said parts being combined substantially as described.

4. In a match-making machine, a hopper, a rotary drum with fluted peripheral portion, a

continuous tape, a device for throwing the splints out of engagement with the drum, consisting of a weighted lever with curved arms, the latter being normally below the periphery 5 of the drum, a spool, a cutter, and a separator between said spool and cutter, substantially as described.

5. In a match-machine, a frame with hopper, a drum fed by said hopper, a swinging arm 10 with rotary spindle, and a weighted lever with notched end passing through said swinging arm and having means adapted to prevent the splints from being fed to the drum, said parts being combined substantially as described.

6. In a match-machine, two substantially parallel tapes, in combination with a pivoted weighted elbow-lever having at its upper end a ball-and-socket joint with projecting arms, 20 and rollers on said arms, substantially as and for the purpose set forth.

7. In a match-machine, a frame, a hopper with oscillating end piece, a rotary drum fed from the hopper, a swinging arm with rotary 25 spindle, a cutter, a separator between said hopper and spindle, and an automatic device having arms for removing the splints in the hopper from contact with the drum, said parts being combined substantially as described.

30 8. A match-making machine consisting of a frame, a hopper with an oscillating end gate,

a rotary drum, a swinging arm with a rotary spool, a rotary cutter, a separator between said spool and cutter, a binding-tape, and a device for throwing the splints out of engagement 35 with the drum, substantially as described.

9. In a match-machine, the combination of a frame, a hopper having an oscillating end piece and an inclined bottom, a rotary drum fed from said hopper, the continuous binding- 40 tape, the device for raising the splints from the drum, a spool, a rotary cutter, a separator between said spool and cutter, and the brush-wheels, substantially as described.

10. In a match-machine, a swinging arm 45 having its lower end mounted on a shaft and its upper end provided with a spindle carrying a spool, sprocket-wheels on said shaft and spindle connected by a chain belt, a splined gear-wheel on said shaft meshing with a train 50 of gearing to impart motion to said sprocket-wheels, washers mounted on each side of the sprocket-wheel on the shaft and one of which bears against the said splined gear-wheel, a clamping-plate mounted against and partially 55 embracing the outer washer, and a clamping-nut bearing against said clamping-plate, substantially as described.
